UNITED STATES PATENT OFFICE.

GEORGE FORD, OF NEW HARMONY, INDIANA.

GATE.

SPECIFICATION forming part of Letters Patent No. 381,063, dated April 10, 1888.

Application filed August 21, 1886. Serial No. 211,551. (No model.)

To all whom it may concern:

Be it known that I, GEORGE FORD, a citizen of the United States, residing at New Harmony, in the county of Posey and State of Indiana, have invented a new and useful Improvement in Gates and Gate-Hangings; and I do hereby declare that the following is a full, clear, and exact description of the construction and operation of the same.

10 My invention is an improvement in gates; and it consists in certain novel constructions and combinations of parts, as will be described and claimed.

In the drawings, Figure 1 is an elevation, 15 partly in perspective, of a gate constructed according to my invention. Fig. 2 is a detail view of the under side of the connecting-bar. Fig. 3 is a detail view of the gate-post. Fig. 4 is a detail view of the lift-bar and its connections. Fig. 5 is a detail, partly in vertical section, on about line $x x$, Fig. 1.

The gate is arranged between two latch-posts, A A, and is made of two sections, B B, joined at their upper ends by a connection-bar, C, and near their lower ends by the hinge-loop D, which encircles the central or hinge post, E. This loop D has lugs d fitting on opposite sides of the gate-sections, as clearly shown in the drawings.

30 For the purpose of overcoming friction I interpose rollers F between the loop and the post, said rollers being usually journaled on supports f, connected with the post E. On the post I support a series of inclines, G, having 35 easy inclined faces g and more abrupt faces g', the said faces g' g' inclining in opposite directions, as shown. A tube, H, extends from the center of the post upward, and is provided in its opposite sides with slots h, extended in the 40 direction of its length. These slots h are preferably inclined or made spiral, as shown in Fig. 1, for the purpose of aiding in partially turning the gate while elevating the same in the operation of the invention. The connecting-bar C is suitably secured at its ends to the gate-sections, and has between its ends an opening, i, formed to fit over the tube H. On the under side of this bar are provided lugs i', encircling the opening i, as clearly shown in

45 Fig. 2. Bearings I', preferably journaled rollers, as shown, are provided on the under 50 side of the connecting-bar C, surrounding the lugs i'. The hanger-rod J extends down into the tube H, and is connected with the cross rod or shaft K, which engages the lugs i', and 55 the walls of the inclined slots h being preferably provided with rollers k k', to reduce the friction of contact with such parts i' and h. To the upper end of the rod J are connected 60 the levers L, pivoted in brackets L', mounted 65 on the tube H.

The operation of this construction will be readily understood. It will be noticed that the gate being pivoted centrally any resisting action of the wind on one side of said pivot 70 will be counteracted by the opposing action of the wind on the opposite portion, so that the gate may be turned as freely in windy as in other weather. I employ four of the inclines G, so that the gate will be given a quarter-turn at each operation. As the hanger-rod is 75 lifted in tube H by the levers or in other suitable manner, the cross-bar will engage under the connecting-bar and with one of the lugs i' thereof. By reason of these lugs the cross-shaft is held from turning under the connecting-bar, and the said bar is moved with the gate around as the shaft traverses the spiral or inclined slots h of the tube H. This lifting of 80 the gate raises and turns it past the crown of the inclines G onto the easy or gradually inclined face g, down which the connecting-bar moves, carrying the gate to its open position, the lugs i' sliding over the cross-shaft, for 85 which purpose one side, i', of each of the said lugs is inclined or beveled, as shown. Thus the gate is opened or given one-quarter of a turn or revolution, and it is closed by a like 90 operation.

What I claim is—

1. The combination of the gate proper, the gate-post, the tube H, having slots h, the inclines G, the bearings I', and the hanger-rod and cross-shaft, substantially as set forth.
2. The combination of the gate, the post, the inclines G, the lugs i', the tube H, having slots h, the hanger-rod, the bearings I', and the cross-shaft, substantially as set forth.
3. The post E, having inclines G, and tube H, provided with slots h, combined with the gate-sections, the connecting-bar fitted over the tube H, and provided with lugs i' and bear-

ings I', the hanger-rod, and the cross-shaft, substantially as set forth.

4. The combination of the central post, the inclines G, the bearings I', for engaging such inclines, the tube H, having inclined slots h, the gate-sections, the loop-hinge fitted over the post and connected with the gate sections,

the lugs i', the hanger-rod, the cross-shaft, and the levers, substantially as set forth.

GEORGE FORD.
